ROSARY PLAQUE

Anthony G. Rosa, Lyndhurst, N. J.

Application March 21, 1956, Serial No. 40,696

Term of patent 14 years

(Cl. D29—23)

Fig. 1

Fig. 2

Fig. 1 is a top plan view of a rosary plaque, showing my new design; and

Fig. 2 is an end elevational view of the same.

I claim:

The ornamental design for a rosary plaque, as shown.
